UNITED STATES PATENT OFFICE.

JACQUES WOUDHUYSSEN AND GASTON ORY, OF PARIS, FRANCE.

VISCOSIMETER.

Application filed July 7, 1927. Serial No. 204,122.

The present invention relates to a viscosimeter, comprising in combination: A cup-like container for the liquid to be tested and which will be preferably heated by 5 means of an electric heating resistance surrounding said cup. The bottom of the cup is provided with a nozzle formed with an internal valve-seat cooperating with a valve forming part of a tubular fitting containing a 10 thermometer. The bulb of the latter contacts with the liquid to be tested, by means of slits or openings provided in the fitting; said fitting with its thermometer is guided through the cover of the cup by means of a suitable 15 socket, having stop devices to maintain the valve in open position and allow the flow of the liquid through the said nozzle provided in the bottom.

The liquid flowing through the nozzle is 20 received in a graduated testing cup, disposed beneath the nozzle and whereof the lower limit graduation is disposed at some distance from the bottom.

A preferred embodiment of the invention 25 will be described hereafter with reference to the accompanying drawing, wherein:

Fig. 1 is a vertical elevation, half in section, of a viscosimeter;

Figs. 2, 3 and 4 are respectively sectional views on lines A—B, E—F and C—D of Fig. 1.

A cylindrical cup-like container 1 has a bottom 3 and a cover 2, both screwed thereon; the bottom 3 is provided with a nozzle 4 allowing the liquid contained in the cup to flow in a testing cup beneath. This nozzle forms internally a conical valve-seat for the conical valve 16, which forms the terminal part of a tubular fitting 17 containing the 40 thermometer 13. The tubular fitting 17 is provided with slits or ports 15, to allow the liquid to enter in contact with the bulb 14 of the thermometer, so that the exchange of heat can be readily ensured. The conical 45 valve 16 is screwed in the threaded end 26 of the fitting 17. The liquid flowing through the nozzle 4 is recuperated in a testing cup 5 lodged in the metallic casing 6 screwed to a flange 25 of the cup-bottom 3. This testing cup will be preferably made of glass, the metallic casing being provided with a suitable opening 9 for observation. The time of 55 flowing of the liquid is measured by the number of seconds that will lapse between the filling of the testing cup from the graduation 8 to that numbered 7.

The thermometer is provided with a superior fitting 18, screwed to the inferior fitting 17 by the screw-thread 27. The fitting 18 is provided with a slit 28 allowing observation 60 of the graduation 19 of the thermometer. The fittings 18, 17 and the conical valve 16 have a common axis and, as the fitting 17 is guided in the socket 29 of the cover 2, said axis corresponds with that of the nozzle 4 65 and the conical seat 30. The summit of the conical valve 16 has an angle such that a partial rotation of the parts 18, 17 and 16, forming valve and valve stem, will realize a tight closing and obturation of the nozzle. 70

The lugs 20 of the fitting 17, after opening the valve, can rest upon shoulders 21 of the socket 29 and, in this way, the valve will remain open to allow the discharge of the liquid. Cuts 31 are of substantially larger openings 75 than the width of the lugs 20, so as to allow a partial rotation of the conical valve at the moment where it is forced on its seat.

The liquid is heated by means of an electric resistance 10 adapted round the cup 1 80 and maintained in position by means of a flange-like extension of the cover 2; said heating resistance can be removed if necessary. A joint or sealing material 22 prevents the liquid to climb along the thermometer 85 and soiling of same.

We claim:

1. A viscosimeter comprising in combination: a cup-like container for the liquid to be tested, means for heating the liquid, a nozzle in the bottom of the container, an internal valve seat in said nozzle cooperating with a valve forming part of a tubular fitting containing a thermometer, the bulb of which contacts with the liquid to be tested, means 90 for opening and closing the valve and a graduated testing cup receiving the liquid flowing through the nozzle.

2. A viscosimeter comprising a cylindrical metallic cup containing the liquid to be tested, a removable electric heating resistance surrounding said cup, a nozzle in the bottom screwed to the cup, a conical valve-seat in said nozzle cooperating with an internal conical valve forming the terminal part of a tubular 100 fitting containing a thermometer the bulb of which contacts with the liquid by means of slits or ports provided in said fitting, a guiding socket for said fitting in the cover of the cup, means for maintaining the valve 110 in open position and a graduated testing cup receiving the liquid flowing through the nozzle.

zle and having its lower limit graduation at some distance from the bottom, said testing cup being disposed beneath the nozzle in a casing screwed to a flange of the cup bottom, 5 substantially as described.

3. A viscosimeter comprising a cylindrical metallic cup containing the liquid to be tested, a removable electric heating resistance surrounding said cup, a nozzle in the bottom 10 screwed to the cup, a conical valve-seat in said nozzle cooperating with an internal conical valve forming the terminal part of a tubular fitting containing a thermometer the bulb

of which contacts with the liquid by means of slits or ports provided in said fitting, a 15 guiding socket for said fitting in the cover of the cup, means for maintaining the valve in open position and a graduated testing cup receiving the liquid flowing through the nozzle, whereby the nozzle, the valve, the thermometer and its fitting have a common axis, substantially as described.

In testimony whereof we signed hereunto our names.

JACQUES WOUDHUYSEN.
GASTON ORY.
